UNITED STATES PATENT OFFICE.

CHARLES WESLEY ALLEN, OF MERRIMAN, NEBRASKA.

ROTARY ENGINE.

SPECIFICATION forming part of Letters Patent No. 764,097, dated July 5, 1904.

Application filed November 7, 1903. Serial No. 180,227. (No model.)

To all whom it may concern:

Be it known that I, CHARLES WESLEY ALLEN, a citizen of the United States, residing at Merriman, in the county of Cherry and State 5 of Nebraska, have invented certain new and useful Improvements in Rotary Engines; and I do hereby declare the following to be a full, clear, and exact description of the invention, such as will enable others skilled in the art to 10 which it appertains to make and use the same.

My invention relates to improvements in rotary steam-engines. It has for its object to promote simplicity of construction, easy-running action, and to effect ready reversing of 15 the engine; and to these ends the invention consists of structural features of novelty, substantially as hereinafter more fully disclosed, and particularly pointed out by the claims concluding the following specification.

20 In the accompanying drawings, illustrating the preferred embodiment of my invention, Figure 1 is a sectional elevation. Fig. 2 is an end elevation. Fig. 3 is a side elevation. Fig. 4 is a vertical section on line $\alpha\alpha$ of Fig. 25 1. Fig. 5 is an enlarged vertical section of one piston. Fig. 6 is a side view of the same. Fig. 7 is a detailed perspective view of the slide-valve. Fig. 8 is a similar view of the piston abutments or wings. Fig. 9 is a detached perspective view of the reversing- 30 valves. Fig. 10 is a similar view of the reversing-valve-actuating lever. Fig. 11 is an end elevation thereof. Fig. 12 represents the piston-packing in side and plan. Fig. 13 is 35 a sectional elevation taken through Fig. 3 on line yy .

In the carrying out of my invention I provide a suitable cylindric casing 1, suitably supported in position, and within the same is arranged a piston 2, whose shaft 2^a bears laterally in said casing and having applied thereto means, as a belt-pulley, for transmitting motion to the machinery and also connected up, as presently disclosed, to a reversing-valve 45 later described. Said piston carries radially-sliding abutments or wings 2^b effective under the impact of steam for imparting rotary motion to said piston. Laterally inserted within each piston of the casings are packing-strips 50 2^c, each being semicircular and adapted to ef-

fect a steam-tight fit between the pistons and their casings, said packings being spring seated or cushioned for that purpose. The abutments or wings 2^b each have at their relatively outer ends suitably spring-cushioned 55 packing-strips 2^c, adapted to fit steam-tight against the inner sides of the casing or wall of the piston-containing chamber. Within the piston-containing chamber of the casing 1 is suitably secured, at the upper end thereof, opposite spaced-apart cam-plates 3, two being arranged edgewise to and upon each side of a spring cushioned or pressed partition 4, arranged transversely of the vertical plane of the casing 1 and dividing off the live-steam- 60 receiving side from the exhaust-steam side of the piston-containing chamber, as shown. The application of pressure to said partition is effected by interposing springs 4^a therebetween and the upper wall of said chamber, said 65 springs being applied to bolt-like studs 4^b, headed or countersunk into said partition and extending through passages therein and having their unheaded ends playing in recesses in said wall, said partition itself also being 70 capable of movement and guided between parallel cleats or pendants 4^c, secured to said wall.

Two ports 5 5^a, serving as steam supply and exhaust, are provided in the casing 1, establishing communication between opposite sides 80 of the piston-containing chamber and the ports 6^a 6^b of the reversing-valve 6, arranged within a housing or chamber 7, superposed upon the piston-casing 1. Said latter ports are adapted to alternately communicate with 85 the ports 8 8^a, produced in the casing 1 and having pipe connection 9 9^a with a second casing 10, containing a like piston as piston 2 arranged in casing 1 and secured upon the same shaft 2^a or an extension thereof provided 90 with a belt-pulley 2^y for transmitting motion or power. Said shaft 2^a has shaft, crank, and pitman connection 11 11^a 11^b with and actuates a slide-valve 12, arranged between the reversing-valve 6 and the steam-supply port 95 13 for controlling the steam-supply, said port having valved pipe connection 14 with a steam-supply source. (Not shown.) Said reversing-valve is conveniently actuated by a hand-lever 15, preferably fulcrumed in position by a 100

shaft 15^a, supported in suitable bearings, as 15^x, and having end cranks 15^b, with their terminals 15^c engaging the rod 15^d, connected to the valve.

5 As will be seen in Fig. 13, the slide-valve 12^x has an exhaust-port 12^x registering with the port 12 in the steam-chest, said chest having also supply-ports 12^b 12^c communicating with ports or passages 5 and 5^a, respectively.

10 It will be understood that latitude is allowed herein as to details, since they may be changed without departing from the spirit of my invention and the latter remain intact and be protected.

15 Having thus described my invention, what I claim as new, and desire to secure by Letters Patent, is—

1. A rotary engine comprising a plurality of pistons carrying abutments, eccentrically-arranged spaced-apart pendants in the upper part of each piston-containing chamber, a common shaft for said pistons, one of the casings of the piston-containing chambers having a steam-supply-controlling valve for said piston, and common steam-pipes connecting the steam-chests of said casings with ports communicating with opposite sides of one of said casings.

2. A rotary engine, comprising a plurality of pistons carrying abutments, spaced-apart eccentrically-arranged pendants in the upper part of each piston-containing chamber, partitions arranged intermediately of said pendants and the live-steam supply and exhaust 35 sides of said chambers and pistons, a steam-supply-controlling valve for said piston, and

a reversing-valve arranged with relation to said controlling - valve and common steam-pipes for the steam-chests of the casings of the piston-containing chambers connecting with 40 ports communicating with opposite sides of one of said casings.

3. A rotary engine, comprising a piston carrying abutments, spaced-apart eccentrically-arranged pendants in the upper part of the 45 piston - containing chamber, a partition arranged intermediately of said pendants and the steam supply and exhaust side of said chamber and piston, a steam-supply-controlling valve for said piston, and shaft crank and 50 pitman connection between said steam-supply-controlling valve and the piston-shaft.

4. A rotary engine, embracing a plurality of pistons equipped with abutments, eccentrically-arranged pendants in the upper part 55 of each piston-containing chamber, a partition arranged in each of said chambers, intermediately of said pendants and the steam supply and exhaust side of each piston and chamber, a steam-supply-controlling valve arranged in 60 connection with one of said piston-chambers, and common steam-pipes for the steam-chests of said casings, connecting with ports communicating with opposite sides of one of said casings.

65 In testimony whereof I affix my signature in presence of two witnesses.

CHARLES WESLEY ALLEN.
